UNITED STATES PATENT OFFICE

CARLO DE CRISTOFARO, OF ST. LOUIS, MISSOURI, ASSIGNOR OF ONE-HALF TO WILLIAM F. SCARPELLI, OF ST. LOUIS, MISSOURI

DESIGN FOR A HARD TOE BALLET SLIPPER

Application filed June 1, 1931. Serial No. 40,054. Term of patent 14 years.

To all whom it may concern:

Be it known that I, CARLO DE CRISTOFARO, a citizen of the United States of America, residing at St. Louis, Missouri, have invented a new and original Design for a Hard Toe Ballet Slipper, of which the following is a specification, reference being had to the accompanying drawings, forming a part thereof.

Fig. 1 is a plan view of a hard toe ballet slipper showing my new design;

Fig. 2 is a side elevation, and

Fig. 3 is a rear end elevation of the same.

I claim the ornamental design for a hard toe ballet slipper, as shown.

CARLO DE CRISTOFARO.
